UNITED STATES PATENT OFFICE.

ALEXANDER WINKLER, OF ST. PETERSBURG, RUSSIA.

IMPROVEMENT IN FEED-WATER APPARATUS FOR STEAM-BOILERS.

Specification forming part of Letters Patent No. 131,489, dated September 17, 1872.

To all whom it may concern:

Be it known that I, ALEXANDER WINKLER, of St. Petersburg, Russia, have invented "a method of resupplying steam-engines with steam that has already been used therein," of which the following is a specification:

This invention has for its object an improved method of utilizing steam that has already been used in a steam-engine. The said invention consists in supplying steam-generators with exhaust steam, or steam that has already been used; in reconducting the exhaust steam of a steam-engine to the original boiler or steam-generator used for supplying the said steam-engine; and in the manner in which these objects are effected, by the means hereinafter specified. It is therefore evident that by this invention the same quantity of steam is repeatedly used in the engine, and I thereby not only effect a considerable saving of fuel, but also obtain many other important advantages, as hereinafter set forth.

In practicing my said invention the exhaust steam or steam that has already been used in a steam-engine is reconducted into a reservoir, which, by means of a suction-pipe, is connected with a pressure apparatus, and with an injector of simple construction, provided with stop-cocks, and extending into the steam-space of the boiler or generator. As the theory, construction, and mode of action of the injector are well known, and form no part of this invention, it will be sufficient to mention here that for the attainment of my purpose—that is to say, for reconducting the exhaust steam into the steam-generator—I use the ordinary apparatus, with the difference that for the supply of the boiler the injector is not made to absorb water but steam that has already been used in a steam-engine.

Description of the Drawing.

Figure 1 is a side elevation of a steam-boiler in connection with an injector and a reservoir for the steam that has already been used in an engine. Fig. 2 is a longitudinal section of the said injector.

A is the steam-boiler of the engine, B the injector, and C the reservoir for the exhaust steam or steam already once used. a is a pressure-tube, which connects the inlet-gland g, Fig. 2, of the injector B with the steam-

space of the boiler A. b is the steam-pipe which makes the connection between the steam-space of the boiler A and the steam-gland h, Fig. 2, of the injector B. d is a suction-tube, which connects the suction-space i of the injector B with the reservoir C. c is a tube, conducting to one or several steam-cylinders of the engine. e is a blow-off cock. f is a valve for cleansing the reservoir C. D and E are the steam and inlet cocks, placed in the ends of the tubes a and b, by means of which communication between the injector B and the steam-space of the boiler A may be opened or interrupted. Between the injector B and the cock E a common "lifting-valve" is inserted, the casing K of which is to be seen in Fig. 1. As the construction of such a valve is generally known and offers nothing new, a detailed illustration thereof is not needed. It is clear that the casing K, with the aforesaid valve, can also be inserted between the cock E and the boiler. As seen in Fig. 1, the pipes a and b enter the boiler A above the water-level X Y. The pipes a and b have a slight inclination toward the injector B, in order that the water of condensation and also all sediment may be conducted into the reservoir C, from which they are discharged or blown through the cock e. The above-described apparatus acts without intermission during the entire operation of the steam-engine. When the latter is put in motion all the blow-off cocks are first opened, and also the cock e, and the pistons of the engine are allowed to make a few strokes, during which the cocks D and E are kept closed. By this means the steam-cylinder and other parts of the engine, and also the pressure or supply apparatus, become heated, and the parts of the latter are freed from any scum and condensation-water. The blow-off cocks are then closed, and the entire arrangement is put in operation by opening the cocks D and E, by which the steam already used in the engine, and accumulated in the reservoir C, is reconducted through the pipe a into the steam-space of the boiler A as it lifts the valve inclosed in the case K. The action of the injector B is regulated by the reservoir C, in which the accumulation of the steam first takes place, so that the action of the same is not interrupted, either during the communication of the reservoir C with the

space behind the piston, or during the "cut-off" of the steam by expansive engines. From this it is evident that the greater the volume of the reservoir C the more regular will be the work of the injector B. By opening the cock D more or less the action of the injector and also the degree of expansion of the steam behind the piston can be regulated in a more perfect manner than by a condenser.

The advantages of my method of utilizing the exhaust steam of an engine by reconducting it to the boiler are, first, a considerable saving of fuel, effected by the reconduction to the boiler of the latent heat used for the production of the steam. According to theoretical calculation this saving amounts to eighty or ninety per cent.; second, a diminution of the required heating-surface of the boiler, and in the quantity of water contained therein, and in the weight and cost of the boiler; third, a saving in the construction of a condensing-engine, in the condenser, and also the air and water pumps, as pressure behind the piston can be

diminished to the desired degree; fourth, being enabled to use repeatedly the same quantity of steam, and, consequently, being less dependent upon the existence of water at the place where the engine and boiler are to be erected; fifth, the possibility of replacing common piston expansion engines by steam-turbines or other rotary steam-motors, which work with larger quantities of steam of less expansion.

Having thus described my invention, what I claim as new, and desire to secure by Letters Patent, is—

The steam-boiler of an engine, provided with an injector, B, exhaust-steam reservoir C, suction-pipe d, pressure-tube a, inlet-gland g, steam-pipe b, gland h, and cocks D E, all combined, constructed, and operating substantially as and for the purpose set forth.

ALEXANDER WINKLER.
